MOP AND WRINGER THEREFOR

Thomas F. Leach, Chicago, Ill.

Application September 8, 1954, Serial No. 454,729

3 Claims. (Cl. 15—1)

The present invention relates to a wringing attachment for mops and is particularly concerned with mops employing pads made of sponge or other suitable resilient absorbent material.

As is well known, practically all cleaning operations involving the use of a mop require that the mop be wrung dry at frequent intervals. The provision of adequate wringing means has proven to be a rather perplexing problem and this is particularly true in the case of sponge mops.

Accordingly, it is among the principal objects of the present invention to provide a mop and wringing attachment that reduces the wringing effort required by providing a high mechanical advantage; that utilizes the mop handle in providing this high mechanical advantage and thereby eliminates bending over during the wringing operation; that permits an accurate, finger-tip control over the wringing operation so that any desired degree of dampness may be easily selected; that cooperates with any type receptacle and eliminates splashing and dripping; and that is economical to fabricate and assemble.

Other objects and advantages of the invention will be apparent during the course of the following description.

In the accompanying drawings forming a part of this specification and in which like numerals are employed to designate like parts throughout the same,

Fig. 1 is a sectional elevational view illustrating the manner of utilizing a mop and wringing attachment in accordance with the present invention;

Fig. 2 is a plan view of the apparatus of Fig. 1;

Fig. 3 is an elevational sectional view taken at right angles to the view of Fig. 1 and omitting the mop;

Fig. 4 illustrates the manner of using the mop of the present invention;

Fig. 5 is a detailed perspective view of the wringing attachment;

Fig. 6 is a detailed perspective view of the sponge pad, sponge plate, and mounting bracket with portions in section and broken away;

Fig. 7 is a sectional view of a sponge pad, sponge plate, and mounting bracket of a modified form of the present invention;

Fig. 8 is a front sectional exploded view taken along the line 8—8 of Fig. 7; and

Fig. 9 is a perspective view of a modified wringing attachment.

It should be understood that the description of the preferred form of the invention is for the purpose of complying with Section 112, Title 35 of the U. S. Code, and that the appended claims should be construed as broadly as the prior art will permit.

Briefly, the present invention provides a novel mop and wringing attachment which permits the mop to be squeezed dry more easily than has heretofore been possible. This is accomplished by means of a wringing attachment which consists of a perforated plate having mounting means on the backside thereof to permit it to

2

be attached to practically all types of known receptacles whether they be round, oval, rectangular, or any other such shape, and a fulcrum arrangement adapted to cooperate with a projection provided on the mop itself. This fulcrum arrangement permits the mop to be pivotally engaged with the wringer plate whereby a relatively small effort applied to the far end of the mop handle is sufficient to completely wring out the mop pad. This result is due to the high mechanical advantage produced in the present arrangement.

Referring now to the drawings and more particularly to Figures 1 and 2 in which the mop 10 is shown in pivotal engagement with the wringing attachment 12 which is mounted on the wall 14 of a suitable container 16. This pivotal engagement is produced by the cooperation of a knob 18 formed integrally with a stem 20 that projects from the mop, with an upwardly flared slot 22 provided on the attachment 12. As is best shown in Figure 5, the flared slot 22 merges with a keyhole-shaped opening 24 and the arrangement is such that the bottom of the slot acts as a neck portion of the keyhole opening 24. In positioning the mop relative to the wringing attachment, the edges of the flared slot engage and guide the stem 20 into its seated position in the opening 24, and the knob 18 is made larger than the opening 24 whereby the mop 10 and plate 12 are prevented from moving relative to each other axially of the opening 24.

Preferably the portion of the knob adjacent the stem 20 is smoothly curved to facilitate the pivotal movement, though the device is also effective whether the knob be a hook, a button, or any type of flaring surface. It should be noted that the neck portion 26 formed by the bottom of the flared slot 22 prevents the pivoting action between the knob 18 and opening 24 from causing the parts to become disengaged.

It is within the scope of the present invention to reverse the relative positions of the knob 18 and the cooperating slots since the pivotal action could also be obtained by providing the bracket 12 with a projecting knob and by providing the mop with a slotted flange.

The wringing attachment as shown in Figure 5 consists of a plate 28, a forwardly offset vertical pad 30 connected to the plate by a horizontal section 32, and a pair of angularly rearwardly projecting hooks 34 secured to the rear surface of the plate 28. The plate 28 conforms generally to the shape of the sponge pad and is provided with a plurality of perforations 36 to provide avenues of escape for the squeezed-out liquid as will be explained hereafter. In the preferred embodiment, this plate is substantially rectangular to match the sponge pad which is also substantially rectangular. The hooks 34 have downwardly turned ends 38 that are inclined at an angle to the plane of the plate 28. This arrangement is preferred for receptacles which are round or oval in shape, such as the container 16 illustrated, though it will also function in the case of rectangular receptacles. In Figure 3 the attachment 12 is shown mounted on the wall of a round receptacle, and the ends 38 are in substantially flush contact with the vertical surface of the wall.

The sponge pad assembly is best shown in Figures 1 and 6 and consists of a pad 40 preferably made of sponge, though any other resilient and absorbent material would be suitable, a rigid plate 42, and a mounting bracket 45. The sponge pad 40 is shown as a rectangular block and is firmly glued to the plate 42, the glue preferably being applied over the entire area of contact between the sponge and the plate. In addition, the plate is provided with a continuous depending peripheral flange 43 that forms a seating well in which the sponge is positioned. The flange 43 and the adjacent peripheral portions of the plate 42 are preferably cushioned by a strip

44 of resilient material such as rubber, or the like, and this cushioning strip protects articles in the region being mopped from becoming scarred or otherwise damaged by the rigid plate 42.

A pair of screws 46 are anchored to the plate 42 by any suitable means and project outwardly thereof to engage suitable openings provided in the mounting bracket 45. The mounting bracket is preferably formed of steel, cast iron or aluminum and has a threaded socket 48 at its upper end that merges with and is angularly directed relative to a substantially flat terminal pad 50.

The mounting bracket is preferably shaped substantially as shown in Figure 6, though in order to reduce costs it may be made from a single tube having one end threaded to correspond to the socket 48 and having the other end pounded flat and provided with a pair of spaced openings to receive the screws 46 of the sponge plate. Such a pipe may be bent until the two ends are in proper angular relationship.

The sponge pad assembly is completed by a pair of washers 52 which space the pad 50 from the plate 42, and a pair of nuts 54 that engage the screws 46 and secure the parts in assembled relationship. A relatively long handle 56 is threaded at its lower end and is adapted to engage the threaded socket 48 of the mounting bracket. The handle 56 is preferably made of wood, though it may also be formed of metal.

As shown in Figures 1 and 2, when the mop is engaged in the wringing attachment by seating the stem 20 projecting from the mounting bracket 48 in the opening 24 with the knob 18 engaging the adjacent portions of the pad 30, downward pressure may then be applied to the upper end of the handle 56 to bring the sponge pad 40 into engagement with the perforated plate 28. The arrangement of the parts is such that the upper portion of the sponge pad 40, as viewed in Figure 1, first contacts the plate 28 with the lower portions successively being compressed as the pivotal motion is completed. Because of this progressive downward squeezing of the pad, a more effective squeezing action is obtained, as the squeezing pressure is concentrated on successive portions of the pad rather than being spread over the entire area of the pad. In addition, the perforations 36 in the plate 28 permit the exuded liquid to escape from the opposite face of the plate.

In Figure 4 the mop is shown in its in-use position, and it should be noted that the knob 18 that projects from the mounting bracket 45 is spaced a substantial distance above the lower surface of the sponge pad 40 so that there is no danger of the knob marring the floor being waxed or scrubbed.

In Figures 7 and 8 a modified arrangement for mounting the sponge pad on the mounting bracket is shown. In this modified arrangement provision is made for replacing the sponge pad. Accordingly, the sponge pad 40 is glued to a substantially rigid plate 60 in the same manner as previously described. The plate 60 is provided with a pair of upwardly projecting studs 62 that are rigidly secured thereto in any suitable manner. As shown, a pair of countersunk screws are used to form the studs 62.

In this embodiment the plate 60 is adapted to seat within the well formed in the rigid plate 42, the only difference being that instead of securing the sponge directly to the plate 42 the sponge may be mounted on the plate 60 which is then adapted to be removably secured to the plate 42. In order to accomplish this the plate 42 is formed with a pair of holes 64 to receive the studs 62, and a pair of wing nuts 66 engage the studs and lock the sponge units in position. Thus, Figures 7 and 8 illustrate an arrangement wherein replaceable sponge units of relatively inexpensive design may be employed with the mounting bracket to permit simple and low cost replacement of the sponge pad.

In Figure 9, a modified form of wringing attachment

is shown wherein the mounting means is extended to provide a foot pad. In this form, the wringing plate 28 and fulcrum arrangement 30, 32 need not be changed, but the mounting means consists of a horizontal portion 70 adapted to rest upon the edge of the wall 14 of the receptacle, a vertical portion 72 adapted to engage the wall 14, and a horizontal foot pad portion 74 adapted to rest on the floor. The portion 70 is provided with a depending arm 76 that engages the inside surface of the wall 14 and the portions 70, 76 and 72 serve to securely mount the wringer attachment, while the portion 74 provides a balancing arrangement by which any tendency of the wringing operation to tip over the receptacle may be easily overcome. It should be noted that in most operations, and with most types of receptacles, the interplay of forces is not sufficient to tip over the receptacle. However, for the instances in which there is a tendency to tip, the foot pad 74 is an important safety measure.

Thus, it may be seen that the objects of the present invention have been accomplished in that the pivoted wringer arrangement utilizes the mop handle to provide a high mechanical advantage that permits finger-tip control of the wringing operation. In addition, the pivoting action is such that successive portions of the sponge pad are subjected to the wringing pressures, thereby considerably reducing the necessary wringing force.

I claim:

1. In a mop-wringing mechanism that includes a mop having a rigid support member, a mophead carried by said member therebeneath, and a handle in rigid connection with said member and extending angularly upwardly from adjacent one edge thereof, and a rigid wringing member separate from said mop and cooperating therewith to compress said mophead; first and second interengaging fulcrum means rigid respectively with said mop and said wringing member and cooperating in compressing said mophead between said members, said first fulcrum means including a stem having an enlarged free end projecting downwardly from said mop to a point outwardly of but adjacent to said edge, and said second fulcrum means comprising a plate portion carried adjacent one edge of said wringing member and having a slot formed therein for receiving and confining said stem in relative pivotal engagement.
2. In combination, a mop having a rigid support member, a mophead carried by said member therebeneath, and a handle in rigid connection with said member and extending angularly upwardly from adjacent one edge thereof, and a rigid wringing member separate from said mop and cooperating therewith to compress said mophead; first and second interengaging fulcrum means rigid respectively with said mop and said wringing member and cooperating in compressing said mophead between said members, said first fulcrum means projecting downwardly from said mop to a point outwardly of but adjacent to said edge, and said second fulcrum means being adjacent one edge of said wringing member, one of said fulcrum means including a stem having an enlarged free end and the other of said fulcrum means including a plate having a slot formed therein for receiving and confining said stem in relative pivotal engagement.
3. In combination, a container having an open top bounded by side walls, a rigid wringing member having mounting means engageable on a wall of said container to support said member within said container, said mounting means including a footpad portion extended to the bottom of said container on the outside thereof; a mop having a rigid support member, a mophead carried by said support member therebeneath, and a handle in rigid connection with said support member and extending angularly upwardly from adjacent one edge thereof; and first and second interengaging fulcrum means rigid respectively with said mop and said wringing member and cooperating in compressing said mophead between said

members, said first fulcrum means projecting downwardly from said mop to a point outwardly of but adjacent to said edge, and said second fulcrum means being adjacent one edge of said wringing member.
